STREET FILL BOX

Charles F. Myers, Baltimore, Md.

Application August 8, 1938, Serial No. 223,779

1 Claim. (Cl. 220—40)

This invention relates to detachable closures for the inlet ends of underground containers for the storage of gasoline and similar commodities dispensed from surface pumps. In order to provide for convenient access and yet at the same time eliminate the hazards presented by pipe ends which project above ground, present installations at filling stations and the like employ what are known as fill boxes secured on the upper ends of storage tank inlet pipes, these being provided with detachable closures disposed flush with the street or runway surface in which the boxes are embedded. As such closures are constantly subjected to strains and shocks from the wheels of heavily loaded vehicles which pass over them the problem of maintaining an adequate water tight and gas tight seal at the closure is serious, bearing in mind that such closures must prevent the escape of explosive gases as well as inward seepage of water, oil and foreign matter, and yet they must not project or extend in any way above the plane of the surface in which they are located.

An object of the present invention is to provide a street fill box having a detachable sealing closure spring tensioned in uniform flatly seated sealing engagement with its box through the agency of locking means engaging the box in a manner to prevent any tilting of the closure with respect to the axis of its box.

Another object is to provide a novel construction of a street fill box of a sturdy, durable character, and which is simple and capable of economic production.

Other objects will be readily apparent to those skilled in the art.

The present disclosure constitutes a practical embodiment of the best means I have thus far devised for reducing the invention to practice, and it is to be understood that within the scope of the invention as claimed various changes and modifications may be made as desired in the structural details.

In the accompanying drawing, wherein like characters of reference designate like parts throughout the several views:

Figure 1 is a top plan view of my improved fill box with closure removed.

Figure 2 is a top plan view of the closure plate.

Figure 3 is a vertical section taken on the line 3—3 of Figure 1.

Figure 4 is a vertical section through the closure with its associated locking means.

Figure 5 is a bottom perspective view of the locking member.

In the illustrated embodiment the fill box comprises a cylindrical pipe casting 6 thickened in cross section of its walls at the lower end portion to provide an internal annular shoulder 7, the reduced bore of the casting being internally threaded as at 8 to take over the upper end of a storage container inlet pipe, not shown.

At its upper end the casting is laterally enlarged to provide an external annular flange 9 for ground seating purposes, the bore of the casting being diametrically increased at its upper end portion to provide a flat internal annular shoulder 10 on which is seated a sealing ring 11 of compressible elastic material, preferably rubber, circumferentially anchored in an annular retaining channel 12 formed in the wall of the enlarged section of the casting bore.

At its upper end portion with an arcuate rib 13 which terminate flush with the shoulder 10 at their upper ends and adjacent the shoulder 11 at their lower ends. Each rib 13 merges at its upper end portion with an arcuate rib 14 extending circumferentially on the inner face of the casting and having a flat top face flush with and forming a continuation of the shoulder 10, the respective ribs 13 being disposed at one end of each arcuate rib 14.

The other end 15 of each arcuate rib terminates in spaced relation from the adjacent longitudinal rib 13 to provide, as seen in Figure 1, relatively large equal arcuate slots 16 at diametrically opposed points. The bottom of each arcuate rib is formed with a somewhat rounded cam edge portion 17 inclined upwardly from its bottom face beginning at a point approximately one third the length of the rib inwardly from the end 15 and continuing to that end, the remainder of the bottom face being parallel to its upper flat face.

The closure comprises a circular plate having a flat top face and adapted to fit snugly within the upper end of the box casting flush with its top edge. This plate 18 has a flat under face around its edge which is adapted to seat on the sealing ring 11 when the closure is applied. Depending centrally from the bottom face of the closure is a circular base 19 having a depending reduced extension 20 whereof at least two opposed sides are substantially straight. A stem 21 extends axially from the portion 20 and is threaded at its lower end to receive a retaining nut 22 backing a washer 23 which seats the lower end of a coil ex-

pansion spring 24 surrounding the stem 21 and bearing at its upper end against the base extension 20.

A floating locking member 25 having a central slot 26 conforming to the configuration of the closure base extension 20 slides axially over and upon the extension, the under face of the member being axially bored for a portion of its thickness to provide a circular housing socket 27 which receives the upper end of the spring 24. The lock member is centrally thickened toward the base 19 against which it normally bears under the influence of the spring 24 acting against the webs 28 at the sides of the slot 26. Ears 29 extend radially from the lock member at diametrically opposite points. One diagonally opposite pair of side edges 30 on the ears is made substantially straight edged with flat side faces while the other diagonal pair of side edges are rounded to form cam surfaces 31. As shown in Figure 4, the combined thickness of the closure base 19 and central portion of the lock member serves to space the ears 29 from the closure plate an axial distance somewhat lesser than the axial distance between the top face of the sealing ring 11 and the bottom face of the arcuate ribs 14.

An important feature of the invention resides in the fact that the overall distance from the tip of one lock ear 29 to the tip of the other is but slightly less than the diameter of the bore of the casting between the shoulders 7 and 10, and the thickness of the ears, axially with respect to the closure, is sufficiently great to preclude any rocking of the lock member when the closure is applied. Otherwise expressed, the lock member is restrained against oscillation on an axis at right angles to the longitudinal axis of the ears, due to the fact that the outer ends of the ears bear against the walls of the casting bore.

The upper face of the closure plate is formed with a tool engageable socket 32 for cooperation with a suitable tool, not shown, of the T head wrench type by which the closure may be turned, and applied or disengaged.

In service, the closure plate is applied by seating it on the sealing ring 11 with the ears 29 of the lock member passed through the arcuate slots 16. The closure is then given a quarter turn to engage the rounded cam surfaces of the locking ears beneath the cams 17 of the arcuate ribs on the casting 6, whereupon the lock member is forced axially downward compressing the strong spring 24. At the completion of a quarter turn the ears 29 will have become engaged beneath the flat under faces of the arcuate holding ribs 14, and the tension of the spring 24

expanding against the washer 23 will pull the closure strongly and firmly down against the sealing ring 11 on which it bears flatly and with a uniform pressure around its entire edge. Thus the closure is maintained firmly seated on the sealing ring under a constant spring tension applied in the axis of the closure until released.

The ends of the locking ears 29 bear against the walls of the casting bore, as previously described, and thus prevent any tilting of the closure with respect to the axis of the casting 6. Accordingly, the closure is held at all times in flat uniform bearing engagement against the sealing ring, and the top face of the closure is maintained flush with respect to the flat top edge of the fill box.

When the closure is to be removed a reverse turn is imparted thereto. The locking ears ride out from beneath the cams 17 until their flat side faces 31 abut against the axial ribs 13, which prevents further turning of the closure. When this abutting engagement occurs the ears 29 will be properly registered with the arcuate slots 16 so that the closure may be lifted freely from the box. The straight inner edges of the lock member webs 28 which form the sides of the slot 26 are engaged at all times with the straight sides of the base extension 20 so that the lock member turns with the closure but is free to be moved axially with respect thereto.

I claim:

A fill box comprising a hollow tubular member having a pipe attachable end, an annular sealing member in its other end, a circular closure plate adapted to seat against the sealing member and rotatable in the end of said tubular member, an arcuate rib extending circumferentially on the inner face of said tubular member, an axial extension depending from said closure plate, a lock member guided on said extension for rotation therewith and for movement axially thereon, spring means between a portion of said extension and the lock member and urging said lock member towards the closure plate, cooperating cam faces on said arcuate rib and lock member for camming said lock member downwardly against tension of the spring means when the closure plate is rotated in one direction, whereby to draw the closure plate firmly down against the sealing member, and said lock member having end portions engageable against a wall of said tubular member and of a sufficient bearing extent to prohibit tilting of said extension and closure plate with respect to the axis of said tubular member.

CHARLES F. MYERS.
